UNITED STATES PATENT OFFICE.

EDWARD G. THOMAS, OF TOLEDO, OHIO, ASSIGNOR TO TOLEDO SCALE COMPANY, OF TOLEDO, OHIO, A CORPORATION OF NEW JERSEY.

PIVOT MOUNTING.

Application filed February 18, 1920. Serial No. 359,581.

This invention relates to means for mounting knife edge pivots such as are used in instruments and machines in which it is desirable to reduce friction to a minimum, and particularly to means for mounting such pivots in scale levers. As such levers are now constructed the knife edge pivots are usually placed in the mould in which the lever is to be cast and are thus fixed in place when the metal of the lever solidifies. In order that the scale may weigh properly, the pivots in the scale levers must be placed with great exactness, and the practice of casting the levers with the pivots in place results in the loss of many castings owing to the pivots having been improperly placed or having shifted in the mould. Furthermore, the pivots lose their temper and often warp during the casting process and must be reshaped and re-hardened, which involves grinding and heat treating operations that, when the pivots are fixed in the lever, are difficult to carry out, especially if the lever be a heavy one. Where a pivot is thus fixed in place it must be formed of a bar of sufficient cross-section to support the weight, and as these bars are of high-grade steel, their cost is considerable. The practice of inserting the pivots in holes drilled in the lever is also followed to some extent, but such inserted pivots must be formed of even heavier bars than are used to form pivots which are fixed in place in casting, and the cost of inserted pivots which are entirely formed of hardened steel is therefore also very great.

The principal object of this invention is to provide improved means whereby pivots containing a minimum amount of expensive metal may be securely and accurately fixed to a scale lever.

Another object is to provide means for securely fixing a pivot to a lever so that the pivot may be readily detached and replaced.

Still another object is to provide means for detachably securing a pivot to a lever so arranged that the parts may be accurately fitted with a minimum amount of machining.

Other objects and advantages will be apparent from the following description, in which reference is had to the accompanying

drawings illustrating preferred embodiments of my invention and wherein similar reference numerals designate similar parts throughout the several views.

In the drawings:

Figure 1 is a side elevation of a lever having pivots mounted thereon according to my invention, parts being broken away;

Figure 2 is an enlarged vertical section on the line 2—2 of Figure 1;

Figure 3 is an end view of the pivot retainer and pivot of my invention; and

Figures 4 and 5 are similar views showing modifications thereof.

Referring to the drawings in detail and particularly to Figures 1, 2 and 3, the lever 1 on which pivots are to be mounted according to my invention is provided with tapered openings for receiving the pivot retainers 2, the central portions of which are tapered, as at 3, to fit snugly in the openings in the lever. Owing to this tapered formation the pivot retainers may be driven into place so that they will be held with all necessary firmness, though they may, when necessary, be readily driven out.

Substantially cylindrical projections 4 are formed at the ends of each of the pivot retainers 2, and aligned longitudinally-extending grooves 5 having their sides substantially at right angles to each other are milled in the sides of the projections 4, one side of each groove being of considerable area to form a surface against which a pivot 6 may be clamped. The pivot retainers 2 may be of relatively inexpensive soft steel.

Each knife edge pivot 6 is formed of a bar of hardened steel with two of its sides parallel, one of these sides having a depression therein adapted to receive the end of a curved clamping member 7 by means of which it is finally clamped against the sides of the groove 5. In the illustrated embodiments the pivot bar is substantially trapeziform in cross section. The bar may, however, in cases where the pivot has little movement, be substantially rectangular. A bolt 8 passing through the cylindrical projection 4 provides a means for drawing the clamping member 7 into place. If desired,

the position of the knife edge may be adjusted by placing shims 9 between the sides

of the pivot bar and the groove in the manner shown in Figure 3. End thrust bearings at the inner ends of the pivot bars 6 are formed by hardened pins 11 which are driven into sockets in the lever 1.

In the modification shown in Figure 4, the extension 4^a of the pivot retainer is not bored and the clamping member 7^a is so constructed that it extends around the projection 4^a to a point opposite the groove where it terminates in a threaded boss 10^a which receives a set screw 8^a by means of which its opposite end may be drawn into firm engagement with the pivot bar 6^a.

In the modification shown in Figure 5, registering bores extend through the projection 4^b and the pivot bar 6^b so that the pivot bar may be clamped in place by means of an ordinary bolt 8^b. In each of the modifications the pivot retainer is so turned that the knife edge of the pivot will lie directly above or below the axis of the pivot retainer.

It will be apparent upon inspection of the drawings that the clamps shown in Figures 3 and 4 act to force the bar against both sides of the groove; that the pivots in any of the forms may be readily removed by loosening the clamp; and that since it is not wedged into place, there is no danger of rust causing it to stick so that it cannot be easily detached.

It is also apparent that since the groove 5 is formed with straight sides at right angles to each other and the knife edge of the pivot bar is formed at one of its corners, the parts may be constructed and fitted together with less machining than would otherwise be necessary, and that since only the thickness and the width of one side need be considered in duplicating the pivot bar, it can easily be replaced when it becomes worn.

While it will be apparent that the illustrated embodiments of my invention herein disclosed are well calculated to adequately fulfill the objects primarily stated, it is to be understood that the invention is susceptible to variation, modification and change within the spirit and scope of the subjoined claims.

Having described my invention, I claim:

1. In a device of the class described, in combination, a lever, a pivot retainer passing therethrough and secured thereto, said pivot retainer having a two-sided groove therein, and a pivot bar secured in said groove.

2. In a device of the class described, in combination, a lever, a pivot retainer passing therethrough and secured thereto, said pivot retainer having a two-sided groove therein, a pivot bar, and means for clamping said pivot bar in said groove.

3. In a device of the class described, in combination, a lever, a pivot retainer passing therethrough and secured thereto, said pivot retainer having a two-sided groove therein, a pivot bar, and means for clamping said pivot bar against both sides of said groove.

4. In a device of the class described, in combination, a lever, a pivot retainer secured thereto, a pivot bar provided with a depression, and a clamping member engaging said pivot retainer and seating in said depression.

5. In a device of the class described, in combination, a lever, a pivot retainer secured thereto, said pivot retainer being provided with a two-sided groove, and a pivot bar of substantially trapeziform cross-section, two only of the sides of said pivot bar being parallel, secured in said groove.

6. In a device of the class described, in combination, a lever, a pivot retainer secured thereto, said pivot retainer having a two-sided groove therein, and a pivot bar of substantially right trapeziform cross-section with two parallel sides and one acute edge having one of its parallel sides clamped against the side of said groove and its acute edge projecting from said retainer.

7. In a device of the class described, in combination, a lever, a pivot retainer secured thereto, said pivot retainer having a two-sided groove therein, a pivot bar having two parallel sides, and a clamping member partially encircling said retainer and engaging one of said parallel sides, the other parallel side lying against a side of said groove.

EDWARD G. THOMAS.
